DOME FOR CONCRETE STRUCTURES.

1,258,923.

Specification of Letters Patent. Patented Mar. 12, 1918.

Application filed September 22, 1916, Serial No. 121,605. Renewed January 28, 1918. Serial No. 214,251.

To all whom it may concern:

Be it known that we, EDWARD C. MARQUA, HANS VON UNWERTH, and JOHN H. BYRD, citizens of the United States, residing at 5 Kansas City, in the county of Jackson and State of Missouri, have invented certain new and useful Improvements in Domes for Concrete Structures; and we do declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

Our invention relates to a dome for concrete structures and more particularly to 20 domes of that character used in the construction of concrete floors, or the like wherein the domes are arranged along supporting soffits to form a mold for the floor joists and intervening floor slabs; the principal object of the invention being to provide 25 a dome which may be assembled with other like domes to form a mold to receive the concrete and to so construct the same that it may be collapsed after the concrete has sufficiently set thereabout and removed 30 from the structure without necessitating the removal of the soffits and supporting studs.

A further object of the invention is to so 35 construct the domes that the parts may be readily assembled and locked together to form rigid and substantial structures which may also be easily and quickly collapsed to facilitate their removal from the concrete, to provide ease in handling and to require a minimum amount of space for storing or 40 shipping.

In accomplishing these objects we have provided improved details of structure the preferred forms of which are illustrated in the accompanying drawings, wherein:—

45 Figure I is a segmental perspective view showing a concrete floor in the course of construction, particularly illustrating the assembling of the domes on supporting members to form the mold for the floor 50 joist and slabs.

Fig. II is a sectional view through a portion of a floor showing a dome in functional position and an adjacent dome collapsed to permit its removal from the 55 structure.

Fig. III is a detail perspective view of a dome, illustrating the manner of assembling and locking the cross webs.

Fig. IV is a detail perspective view showing a modified form of joining the top sections of the dome.

Referring more in detail to the drawings:—

1 designates a dome constructed according to our invention which in its preferred form is of rectangular shape and comprises a top plate 2, outwardly sloping side members 3—3' and transverse web plates 4—4' which are mounted within and spaced slightly from the ends of the dome to support 70 the top and side sections in their functional position.

In the preferred construction of the dome, the top 2 comprises separate sections 5—5' which are joined along the longitudinal center by hinges 6 as shown, or by any other suitable means that will permit the top sections to collapse downwardly. Likewise joined to the outer longitudinal edges of the top sections 5—5' by hinges 7 80 are the side members 3—3' which comprises longitudinally extending upper and lower sections 8—8' joined by hinges 9, at the outer face of the dome to permit the said side members to collapse inwardly along 85 the longitudinal joint and to fold toward the top sections.

The side sections 3—3' are preferably inclined outwardly toward their free ends so that the dome may be more easily removed from the concrete after the latter has become set and the lower edges of the side sections 8' and the upper longitudinal edges of the top sections 5—5' are rounded as shown respectively at 10 and 11, so that 95 the parts may be collapsed without binding, springing or otherwise causing injury to the dome or floor surface.

In order to support the side and top sections of the dome in functional position we 100 provide the cross members or webs 4—4' which are removed from the dome when the latter is to be collapsed or stored; the said webs comprising vertically arranged plates having a length equal to the inside 105 width of the dome and diagonally cut end faces corresponding to the outward slope given the side sections, so that the said webs may fit tightly against the top and side sections to hold the latter rigidly in their func- 110

tional position and prevent any possible inward collapse.

Each of the webs 4-4' is provided, preferably on its outer face, with a stiffening strip 13, the ends of which are adapted to seat on the upper ends of blocks 14-14' secured at opposite sides of the dome on the lower side sections 8', so that when the webs are inserted in place within the dome the ends of the strips 18 seat on the side blocks and hold the web tightly against the top plate.

In order to lock the side sections to the cross webs we provide hooks 16 which are mounted at opposite ends of each of the web sections and are adapted for seating in hook eyes 17 mounted in place against the blocks and the hooks seated in the eyes, the side sections are held tightly against the ends of the webs and the webs are in turn secured tightly against the blocks and the entire dome is made rigid and substantial.

In Fig. IV we have shown a modified form of joining the top sections, which comprises hooks 18 secured to one of the sections which take into eyes 19 on the opposite section, so that the parts will be held tight together; it being apparent that the supporting webs when in place will prevent collapsing of the parts, but when removed will permit the sections to be collapsed downwardly and removed.

In using domes of this character presuming the parts to be so constructed and assembled, a plurality of the domes are arranged, end to end along parallel spaced soffits 20 as illustrated in Fig. I; the soffits being supported by any suitable means preferably by joists 21 and posts 22; the arrangement of the domes with the soffits being such that the adjacent sides of two rows of the domes and a supporting soffit will form the sides and bottom of a mold for a floor joist while the tops of the domes form the bases of molds for the floor slabs.

After the domes have been assembled on the soffits, concrete is poured thereover to fill the spaces between the dome rows and to cover the tops thereof to a thickness sufficient to form the floor slab.

After the concrete has sufficiently set, the domes are removed, by releasing the end hooks 16 from the eyes 17, so that the webs may be unseated from the blocks 14 and removed from the dome, thereby allowing the side members and top to be collapsed inwardly, as shown in Fig. II, so that the dome may be removed from the set concrete.

It is apparent that by so constructing the devices, in erecting a structure, a builder may use the domes on one floor and as soon as the concrete has sufficiently set thereabout they may be removed, while the soffits and supporting studs are left undisturbed to support the green floor. After removing the

domes from the first floor they may again be used in a succeeding floor, and in this manner save the cost of additional dome forms or the waste of time ordinarily given when non-removable or ordinary domes are used, 70 to allow the concrete to set sufficiently to permit the removal of the floor supports.

It is also apparent that the hinged connection of the members and the rounding off of the corners of the side and top sections as 75 shown, provides for an easy collapsing of the parts, so that they may be readily removed from the structure and stored or shipped conveniently and are always in condition that reassembling may be quickly 80 accomplished.

While we have shown the dome parts jointed by hinges, we do not wish to limit the device to this particular form of connection, as it is apparent that various other 85 means could be employed such as by hooks, or pin joints to hold the parts together in functional position and at the same time provide the collapsible feature which is the gist of the present invention.

Having thus described our invention what we claim as new therein and desire to secure by Letters-Patent, is:—

1. A dome for concrete structures comprising longitudinally divided top and side sections, inwardly operating hinges connecting the top and side sections to permit the dome to collapse inwardly at the top and sides, and removable web plates mounted transversely beneath said top to support the 100 said sections in functional position.

2. A dome for concrete structures having a top comprising downwardly-collapsible, hinged sections, side members hinged to the top sections, each comprising longitudinally 105 extending, hinged sections adapted for collapsing inwardly and toward the top sections, spaced web members removably mounted transversely beneath the top sections, and means for supporting said web 110 sections against the said top and side sections.

3. A dome for concrete structures comprising a top section having a hinged joint extending longitudinally thereof, to permit 115 a downward collapse of the said top, side sections hinged connected with the said top section at its longitudinal edges; each having a longitudinally hinged joint to permit inward collapse of the side sections, 120 blocks secured to opposite inner faces of the lower side sections, and removable web plates mounted transversely within the top and side sections, each having longitudinally extending strips mounted thereon adapted 125 for seating on said blocks to support said webs against said top sections, for the purpose set forth.

4. A dome for concrete structures comprising a top section having a hinged joint 130

- extending longitudinally thereof to permit a downward collapse of the said top, side sections hingedly connected with the said top section at its longitudinal edges, each 5 having a longitudinally hinged joint to permit inward collapse of the side sections, blocks secured to opposite inner faces of the lower side sections, removable web plates mounted transversely within the top and 10 side sections each having longitudinally extending strips mounted thereon adapted for seating on said blocks to support said webs against the said top section, hooks mounted at opposite ends of said web plates, and eyes 15 mounted in said side sections adapted to receive said hooks, for the purpose set forth.
5. In a dome for concrete structures, a downwardly collapsible top section having rounded longitudinal edges, side sections hinged to the top section and collapsible inwardly along a longitudinal joint in said side sections, each of said side sections having a rounded lower edge, for the purpose set forth. 20
6. In a dome for concrete structures, a downwardly collapsible top section having rounded longitudinal edges, side sections hinged to the top sections at points inset from the outer edges of the top sections and collapsible inwardly along a longitudinal 25 joint in said side sections, each of said side sections having a rounded lower edge, for the purpose set forth. 30
- In testimony whereof we affix our signatures.
